UNITED STATES PATENT OFFICE.

CHARLES S. GOODING, OF BROOKLINE, MASSACHUSETTS, ASSIGNOR TO JUDSON L. THOMSON MFG. CO., A CORPORATION OF MASSACHUSETTS.

RIVETING-MACHINE.

1,180,028.

Specification of Letters Patent. Patented Apr. 18, 1916.

Application filed July 27, 1914. Serial No. 853,539.

To all whom it may concern:

Be it known that I, CHARLES S. GOODING, a citizen of the United States, residing at Brookline, in the county of Norfolk and State of Massachusetts, have invented new and useful Improvements in Riveting Machines, of which the following is a specification.

This invention relates to a machine for riveting pieces of sheet material together. In riveting two pieces of sheet material together there is oftentimes a space between the adjacent surfaces of the said two pieces of sheet material before they are riveted which it is desirable to close up before the rivet is clenched. Moreover, in clenching a rivet it is desirable that the head of the rivet should be firmly pressed against the outer surface of one of said pieces of sheet material before the clenching of the opposite end of the rivet against the face of the other piece of sheet material begins. Otherwise, the rivet is liable to buckle between the end and the head and make an imperfect job in this respect, and also it will begin to clench as soon as it passes the outer surface of the under piece of material and make a very small "curl over" in the clenching operation.

The desirable manner of performing the riveting operation is to position the rivet in the holes designed therefor in the two pieces of sheet material and clamp the two pieces of sheet material firmly together, with the clenching end of the rivet projecting beyond the lower surface of the sheet metal plate against which it is to be clenched and then while the parts are thus positioned to move an anvil toward and into engagement with the projecting end of said rivet so that the entire amount of projection of the clenching end of the rivet shall be turned over or clenched against the face of the metal plate after the rivet has been positioned in the plates and after the plates have been clamped firmly together.

It is the object of this invention to provide a riveting machine which shall perform the riveting operation in the manner hereinbefore set forth.

The invention consists in the combination and arrangement of parts set forth in the following specification and particularly pointed out in the claims thereof.

Referring to the drawings: Figure 1 is a

front elevation of my improved riveting machine. Fig. 2 is a left hand side elevation of the same. Fig. 3 is a sectional elevation taken on line 3—3 of Fig. 1. Figs. 4, 5 and 6 are detail sectional elevations 60 illustrating the relative positions of the pairs during the riveting operation.

Like numerals refer to like parts throughout the several views of the drawings.

In the drawings, 10 is the frame of the machine, 11 is the driving shaft journaled to rotate in suitable bearings 12 and 13 in the frame of the machine.

14 is a pinion fast to the driving shaft and meshing into a gear 15 which is journaled to rotate upon a shaft 16 and forms one member of a clutch 17. The other member 18 of said clutch is fastened to the shaft 16. The two members 15 and 18 are clutched together as one piece by suitable mechanism 70 (not shown in the drawings, but well known to those skilled in the art), this mechanism being operated from a treadle (not shown in the drawings) by means of a treadle rod 19.

The rivets are driven during the setting operation by a driver 20 which is fastened to a slide 21 guided in ways 22 in the frame 10. The slide 21 has a vertical reciprocatory motion imparted thereto by a pair of toggle links 23 and 24 which are connected to a link 25 by a pivotal pin 26. The link 24 is pivoted at 27 to the frame of the machine, while the link 23 is connected to the upper end of the slide 21 by a pin 28. The link 25 is pivotally connected at its opposite end to a crank-pin 29 which is fastened to a cam plate 30, said cam plate being, in turn, fastened to the shaft 16. By this mechanism a reciprocatory motion is imparted to the slide 21 and hence to the 85 driver 20.

The rivets are fed from a hopper 31 down a raceway 32 and are separated by a slide 33 to be fed down a raceway 34 into a carrier 35 which consists of two carrier blocks 100 36 and 37 fast to springs 38 and 39, respectively, said springs being fastened by bolt 40 to a carrier slide 41. The carrier slide 41 has a pin 42 fast thereto which projects through a slot 43 in the frame of the machine and constitutes a stop to limit the upward movement of the slide 41. Said slide 41 also has a pin 44 fast thereto which projects into a slot 45 in the lever 46 which is pivoted at 47 to the frame of the machine 110.

and at its opposite end is provided with a cam roll 48 which bears against the cam 30. A spring 49 is fastened at one end to the lever 46 and at the other end to the frame and acts to hold the roll 48 in engagement with the cam 30 during its operation.

The rivets are transferred from the raceway 32 to the raceway 34 one at a time by 10 the slide 33 which is operated by a lever 50 pivoted at 51 to the frame of the machine, and has a rocking movement imparted thereto in one direction by a spring 52 and in the opposite direction by a projection 53 on the 15 rear side of the link 25. The operation of the slide 33 in transferring the rivets from the raceway 32 to the raceway 34 is well known to those skilled in the art and, as it forms no part of this invention, requires 20 no further description.

A stationary work-support 54 is fastened to an arm 55 forming a portion of the frame 10 and said work-support terminates at its outer end in a sleeve 56 which surrounds 25 an anvil 57 formed upon the upper end of a tube 58 which is slidably mounted in the outer end of the arm 55. Within said tube is inclosed a spring 59 the lower end of which bears against an adjusting screw 60, 30 and the upper end of which bears against a collar 61 fast to a guide pin 62 which projects upwardly through the anvil and normally beyond the upper surface 63 of the work-support 54. The lower end of the tube 35 58 has ears 64 to which a toggle link 65 is pivoted by means of a pin 66. The lower end of said toggle link is pivoted to another toggle link 67 and to a link 68 by means of a pin 69. The lower end of the toggle link 40 67 is pivoted by means of a pin 70 to downwardly projecting arms 71. The link 68 is made in two parts joined together by a turn-buckle 72 and is connected at its rear end by a pin 73 to a lever 74 pivoted at 75 to the 45 frame of the machine and provided at its upper end with a cam roll 76 which bears against a cam 77 and is held in engagement therewith by a spring 78. By rotating the turn-buckle 72 in the proper direction, the 50 tube 58, with the anvil 57, can be raised or lowered to bring the same nearer to or farther from the upper surface 63 of the work-support 54, and also nearer to or farther from the driver 20. Normally the upper surface 63 of the work-support 54 is located above the upper surface of the anvil 57 and between said anvil and the lower 55 end of the driver 20.

The rivets used in this embodiment of 60 my invention are tubular rivets and the operation of riveting is illustrated in three steps in Figs. 4, 5 and 6. As hereinbefore set forth the rivets descend the raceway 34 and enter a chamber or pocket 79 located between the carrier blocks 36 and 37.

The work, consisting of a plurality of plates of sheet metal 80 and 81 which are to be riveted together, is placed upon the work-support 54 in the position illustrated in Fig. 4, with the under surface of the plate 81 70 resting against the upper surface 63 of the stationary work-support 54. In this position of the parts it will be seen that the work engaging surface of the work-support lies in a plane between the driver 20 and the work engaging surface of the anvil 57. The guide pin 62 at that time projects 75 through two layers of sheet material 80 and 81.

The tubular rivet 82, held in the pocket 80 of the carrier 35 and between the blocks 36 and 37, is moved downwardly by the lever 46 until the guide pin 62 enters the bore of said tubular rivet, as illustrated in Fig. 4. The driver 20 at the same time is 85 moved downwardly by its slide 21 which is actuated as hereinbefore described by the toggle links 23 and 24 and the actuating link 25, crank-pin 29, cam 30 and shaft 16, and as said carrier and driver descend the 90 rivet is placed upon the upper end of the guide-pin 62 and is guided by said guide-pin through the holes 83 and 84 provided in the plates 80 and 81 and after the rivet is thus positioned the driver 20 continues to 95 descend, pushing the rivet out from between the carrier blocks 36 and 37 and pushing the guide-pin 62 downwardly against the action of the spring 59 until the parts assume the relative positions illustrated in Fig. 5, in 100 which it will be noted that the rivet 82 has been pushed through the holes 83 and 84 in the plates 80 and 81 and that the under side of the head of said rivet bears against the upper surface of the plate 80, while the end 105 of the rivet which is to be clenched projects through the plate 81 a sufficient distance to be formed into a "curled over" clench by the final step in the riveting operation, the plates 80 and 81 being clamped together. 110 Up to this point the anvil 57 remains stationary. As soon, however, as the rivet is inserted in place and the plates are clamped together by the driver, as illustrated in Fig. 5, the anvil is moved upwardly and engages the downwardly projecting end of the rivet 82, whereupon said projecting end will be curled over and riveted against the under surface of the plate 81. This movement of the anvil is accomplished through the cam 115 77, lever 74, link 68 and toggle links 65 and 67, and in this operation the projecting lower end of the rivet 82 encounters the anvil 57 and said anvil clenches the rivet as hereinbefore described in a manner well known 120 to those skilled in this art, thus firmly clamping and riveting the plates 80 and 81 together without any tendency to cramp the rivet 82 or to make it buckle prior to the 125 clenching operation.

As soon as the plates have been riveted together, as hereinbefore described, the driver 20 moves upwardly, releasing the pressure upon the rivet 82 and the plates 80 and 81, while the anvil 57 is moved downwardly by the mechanism hereinbefore described. The plates are then removed from the guide-pin by the hand of the operator and are moved along by said operator until the guide-pin is caused to enter another hole in said plates in readiness for the reception of another rivet and the operation of the different parts hereinbefore described is repeated to feed, position and clench another rivet in the plates 80 and 81.

Having thus described my invention, what I claim and desire by Letters Patent to secure is:

1. A machine for setting a tubular rivet in a piece of sheet material having, in combination, a stationary work-support, an anvil, a driver oppositely disposed to said work-support and anvil, mechanism constructed and arranged to move said driver toward said anvil and mechanism constructed and arranged to move said anvil toward said driver after said driver has completed said movement toward said anvil and a guide-pin projecting through said anvil in alinement with said driver and slidable in said anvil.

2. A machine for setting a tubular rivet in a piece of sheet material having, in combination, an anvil, a stationary work-support, a driver oppositely disposed to said work-support and anvil, the work-engaging surface of said work-support being normally located in a plane nearer said driver than is the work-engaging face of said anvil, mechanism constructed and arranged to

move said driver toward said anvil and work-support and mechanism constructed and arranged to move said anvil toward said driver after said driver has completed said movement toward said anvil and a guide-pin projecting through said anvil in alinement with said driver and slidable in said anvil, the upper end of said guide pin projecting normally beyond the upper surface of said work-support.

3. A machine for setting a tubular rivet in a piece of sheet material having, in combination, a rivet carrier, a driver, an anvil, a tube upon the upper end of which said anvil is formed, a guide pin projecting through said anvil in alinement with said driver and slidable in said anvil, a spring interposed between said tube and guide-pin, a stationary work-support adjacent to said anvil and located normally in advance of said anvil relatively to said driver, said anvil and work-support being oppositely disposed to said rivet carrier and driver, the upper end of said guide-pin projecting normally beyond the upper surface of said work-support, means to move said driver toward said anvil and work-support and means to move said anvil toward said driver after said driver has completed said movement, whereby a rivet may be inserted in said sheet material and subsequently clenched therein.

In testimony whereof I have hereunto set my hand in presence of two subscribing witnesses.

CHARLES S. GOODING.
